(57) **CLAIM**

The ornamental design for an exterior vehicle mirror attachment, as shown and described.

DESCRIPTION

FIG. 1 is a front elevational view of an exterior vehicle mirror attachment showing my new design which is mountable on the right original equipment mirror of a motor vehicle;

FIG. 2 is a perspective view of the front, top and one side of the exterior vehicle mirror attachment design of FIG. 1;

FIG. 3 is a perspective view of the front, top and other side of the exterior vehicle mirror attachment design of FIG. 1;

FIG. 4 is a rear elevational view of the exterior vehicle mirror attachment design of FIG. 1;

FIG. 5 is a rear perspective view of the exterior vehicle mirror attachment design of FIG. 1;

FIG. 6 is a rear perspective view of the exterior vehicle mirror attachment design of FIG. 1;

FIG. 7 is a top plan view of the exterior vehicle mirror attachment design of FIG. 1;

FIG. 8 is a bottom plan view of the exterior vehicle mirror attachment design of FIG. 1;

FIG. 9 is an elevational view of one side of the exterior vehicle mirror attachment design of FIG. 1;

FIG. 10 is an elevational view of the other side of the exterior vehicle mirror attachment design of FIG. 1;

FIG. 11 is a perspective view of the front, top and one side of an exterior vehicle mirror attachment showing my new design which is mountable on the left original equipment mirror of a motor vehicle;

FIG. 12 is a perspective view of the front, top and other side of the exterior vehicle mirror attachment design of FIG. 11;

FIG. 13 is a rear perspective view of the exterior vehicle mirror attachment design of FIG. 11;

FIG. 14 is a rear perspective view of the exterior vehicle mirror attachment design of FIG. 11;

FIG. 15 is an elevational view of one side of the exterior vehicle mirror attachment design of FIG. 11;

FIG. 16 is an elevational view of the other side of the exterior vehicle mirror attachment design of FIG. 11;

FIG. 17 is a top plan view of the exterior vehicle mirror attachment design of FIG. 11; and,

FIG. 18 is a bottom plan view of the exterior vehicle mirror attachment design of FIG. 11;
